BALL DRIVING DEVICE

Horace A. Bodge, White Plains, N. Y.

Application August 5, 1936, Serial No. 94,334

5 Claims. (Cl. 273—129)

The present invention relates to ball driving devices for games of variable types adapted for either indoor or outdoor amusements, and includes a portable standard having a base member disposed to bear upon the floor or ground and provided with a driving-head hingedly supported from said stand and adapted to be disposed adjacent the ball to be driven thereby.

The objects of the invention include a manually operated handle slidably mounted for vertical movement within the standard and adapted by downward pressure to outwardly project the driving-head against the ball.

The objects also include manual operating means that provides a relatively undisturbed aim for the driving force applied against the ball, and resilient means that affords both a return movement of the operating parts of the device and a measure of control for the downward operative movement of the handle.

For further comprehension of the invention, and of the objects and advantages thereof, reference is had to the following description and accompanying drawing, and to the appended claims in which the various features of the invention are more particularly set forth.

Referring to the drawing in which similar characters of reference designate like parts throughout the several views:

30 Figure 1 is an elevational view embodying my invention, shown partially in section.

Figure 2 is a similar view taken at right angles to that of Fig. 1.

Figure 3 is a reduced scale view showing the driving-head in projected dotted line position.

In Fig. 1 numeral 10 designates a tubular standard having at its lower end a base-plug 11 detachably secured within the tube by the removable pin 12. A manually controlled operating handle 13 is provided for the tubular standard, the upper end of the latter being disposed to slidably receive for longitudinal guiding movement the lower end of the operating handle.

Also provided for the standard is a driving-head 14 carried from the lower end of the arm 15, the upper end of the latter being bent and perforated at 16 and extended through a laterally elongated slot 17 formed in a wall of the standard where it is connected to the bottom of the operating handle by the screw 18 which passes through the perforation 16.

For supporting the several parts of the device within the standard in the normal manner indicated in Fig. 1, a guide block 19 is mounted for vertical sliding movement within the standard

and is provided with an upper angular face 20 engaging the bent portion of the driving-head arm 15, the lower face 21 of the block being flattened and engaged by one end of a helical spring 22, the opposite end of the latter thrusting against the upper face of base-plug 11.

In assembling the several parts within the standard, the operating handle 13 is inserted in the upper end of the latter, and the bent end of the driving-head arm 15 inserted through the slot 17 of the standard, in which positions the two members may be secured together by the screw 18 from the open base of the standard, after which the block 19, spring 22 and base-plug 11 may be successively inserted and secured together by the pin 12.

With the several parts thus connected together and mounted within the standard, the driving device presents a comparatively simple and compact construction, free from exterior complication, readily shiftable from place to place and normally maintained in operative position whereby a manual downward pressure upon the operating handle will cause the bent end of arm 15 to rotate about the lateral hinge slot 17 and project the driving-head 14, as indicated in dotted lines in Fig. 3. The projecting action of the driving-head is effected in opposition to the spring 22, the latter suitably tensioned and cooperating with the block 19 both to return the several operative parts to their normally operative positions and to effect a smoothly operating hinge joint.

In its operation the base or base plug 11 of the device is securely held by the operating handle against the floor or ground surface over which the ball is to be driven, the driving-head being positioned adjacent the ball and in line with the desired path thereof and in which position the driving-head is subjected to a variable manual projecting force applied by means of both hands of the operator upon the handle to insure stability of the standard without disturbing said alinement or aim.

By varying the manually applied force the travel of the ball may be regulated and its action readily controlled.

It is to be understood that while I illustrate and describe the preferred embodiment of the invention, it is susceptible of various changes as regards its form, proportions, detail construction, and arrangement of parts without departing from the essential spirit and scope or sacrificing any of the advantages of the invention.

I claim:

1. A ball-driving device comprising a tubular

55

standard having a base member at its lower end and provided intermediate its ends with a slot extending through an outer wall thereof, a driving-head having an upwardly projecting arm 5 provided with an inwardly bent portion extending through the slot in said standard, a guide-block slidably mounted within said tubular standard and engaging the inwardly bent portion of the driving-head arm, an operating handle slidable 10 in the upper end of said tubular standard and connected at its lower end to the inwardly bent portion of the driving-head arm, and a compression spring disposed within said tubular standard and between said base member and guide-block and normally adapted to raise said operating handle and retract said driving-head, and upon the manual downward movement of the operating handle to compress said spring and outwardly project said driving-head from said 15 standard to drive the ball.

2. A ball-driving device comprising a tubular standard, a driving-head normally disposed in retracted position exteriorly adjacent the lower end of said standard, the said head having an 25 arm section extending inwardly of said standard for the pivotal support thereof, an operating handle slidable lengthwise within said standard and disposed to receive the lateral support and downward force from both hands of the operator, 30 and coupling means between said handle and the inwardly extending arm-section of said head.

3. In a ball-driving device, a tubular standard having a slot extending through the wall thereof, a driving-head having an arm-section leading 35 through said slot and inwardly of said standard for the pivotal support of the head, an operating handle slidable lengthwise within said tubular

standard, coupling means between said handle and the inwardly extending arm-section of the driving-head, and resilient means within said standard disposed to upwardly urge said operating handle and retract said driving-head. 5

4. A ball-driving device comprising a tubular standard having a base member, a driving-head supported exteriorly adjacent said standard for engaging a ball, the said head having an arm-section extending inwardly of said standard, an 10 operating handle slidable lengthwise within said standard for manual downward movement, coupling means between said handle and the inwardly extending arm-section of the driving-head, a guide-block slidable lengthwise within 15 said standard, and a compression spring disposed between the said base-member and the guide-block and upwardly urging the latter to effect the retraction of the driving-head by the release of the downward manual pressure on the operating handle. 20

5. A ball driving device comprising a tubular standard, a driving-head supported thereby and normally disposed in retracted position exteriorly adjacent said standard, the said head having an 25 arm-section extending inwardly of said standard, an operating handle manually slidable lengthwise within said standard and having coupling means to said inwardly extending arm-section of the driving-head, and a compression spring disposed 30 within the latter and normally acting in opposition to the inward movement of said operating handle, and upon the release of said inward manual movement to retract said driving-head by the reaction of said spring. 35
